CATCH

William Shoemaker, Dayton, Ky., assignor to De-
cometal Incorporated, Dayton, Ky., a corpora-
tion of Kentucky

Application July 3, 1937, Serial No. 151,912

1 Claim. (Cl. 292—175)

This invention relates to catch devices, and more particularly to a catch which is adapted for use with a lady's compact. Present day women's compacts ordinarily contain a compartment adapted to be filled with loose powder and this compartment is provided with a lid so that the loose powder will not spill out of its compartment. The lid must be provided with a catch to hold the same in closed position, and to permit 10 opening of said lid when access is desired to the powder contained in the powder compartment.

A catch for this purpose should be extremely simple and unfailing in operation, and it is therefore an object of my invention to provide a novel 15 catch which is extremely simple in construction and therefore cheap to manufacture, which is certain in its operation and very easy to operate.

Another object of my invention includes the provision of a catch as above outlined, which will 20 not require the use of the finger nail in prying the catch open, and although my catch may be operated by the finger nail if desired, it operates so easily that there is no danger of breaking the finger nail.

25 These and other objects of my invention which will be described hereinafter or which will be apparent to one skilled in the art upon reading these specifications, I accomplish by that certain construction and arrangement of parts of which 30 I shall now describe an exemplary embodiment.

Reference is now made to the drawing forming a part hereof, and in which:

Figure 1 is a plan view of a portion of a compact showing my novel catch in use.

35 Fig. 2 is a cross-sectional view taken on the line 2—2 of Fig. 1.

Fig. 3 is a view similar to Fig. 2 showing the lid of the compact open.

40 Fig. 4 is a cross-sectional view taken on the line 4—4 of Fig. 2, showing the spring element of the catch.

Fig. 5 is a fragmentary view of a portion of the compact shell showing the slot through which the catch operates.

45 Fig. 6 is a detailed elevational view of the catch member itself.

Fig. 7 is a detailed perspective view of the spring member.

In Fig. 1 I have shown a compact shell 10 which 50 contains a powder compartment 11, and is provided with a lid 12. The lid member 12 may be centrally depressed as shown at 12a, and have an annular flange 12b adapted to seat upon a resilient annular pad 13, located in an annular ledge 55 13a in the shell 10. The lid 12 may be hinged in

any conventional manner at 14. The pad 13 serves the dual purpose of preventing leakage of loose powder from the compartment 11 when the lid 12 is closed, and of providing a degree of resilience whereby the lid 12 will spring up when 5 the catch is released.

The catch proper which is shown in detail in Fig. 6, comprises a member 15 having an enlarged head 16, and a pin portion 17, having a neck of reduced diameter at 18. The portion 16 is preferably in the form of a truncated cone, the conical surface of which is inclined at an angle of 45° to the vertical, to facilitate closing of the lid 12 by a cam action. The under side of the member 16 is preferably flat and it is the under side 15 of the member 16 coacting with the upper side of the portion 12b of the lid which serves to hold the same in closed position.

In the shell 10 I provide an elongated hole 19 which in its shorter dimension is large enough 20 to accommodate the portion 17 of the catch 15, and which in its longer dimension is sufficiently long to permit the catch member 16 to be retracted to a point where the lid 12 may spring open.

25 The member 15 is held in position and urged toward the left as seen in the various figures, by means of a spring member 20 shown in detail in Fig. 7. The member 20 is of substantially hairpin shape and is provided at the end of one arm 30 thereof with a turned over flange 21, having a slot 22 therein. The slot 22 is of a width sufficient to accommodate the narrow neck portion 18 of the member 15, and the member 21 is of a width greater than the width of the hole 19. The other 35 arm of the spring member 20 may be provided with a turned over flange 23, which bears against the inside of the shell 10 as indicated at 24. In practice it is unnecessary that the member 23 be fastened in place since the normal resiliency of 40 the spring member 20 will serve to hold it in place. If there is no wall to serve as an abutment as at 24, the portion 23 may be soldered to a flat surface. Furthermore the member 21 is retained 45 within the neck portion 18 of the catch 15 thereby also preventing the spring member from being dislodged.

When it is desired to open the lid 12, it is merely necessary to push the member 15 toward the 50 right as seen in the various figures until the edge of the portion 16 clears the edge of the lid, and then the resilience of the pad member 13 will cause the lid to spring upwardly a slight amount whereupon it may be raised with the fingers. If 55

desired the lid member 12 may be sprung slightly to assist in this springing action.

It is to be understood that the compact or indeed the device upon which the catch may be used, whether it is a compact or not, forms no part of my invention but that my catch may be used in connection with any kind of closure, although it is particularly adapted for use in compacts by virtue of its cheapness, simplicity and ease of operation.

It is to be understood that modification of my device may be made without departing from the spirit of my invention, and that I do not intend to be limited otherwise than as pointed out in 15 the claim which follows.

Having thus described my invention, what I claim as new and desire to secure by Letters Patent is:

A catch for the frame element and closure of compacts and the like comprising a pin having a 5 head to cooperate with said closure and a necked portion, a spring, said pin slidable laterally through an elongated hole in said frame element, the spring being of the leaf type and having a slotted element to cooperate with the necked portion of said pin to hold the same in place within said elongated hole, and said spring urging the pin into operative position to releasably hold said closure closed upon said frame element.

WILLIAM SHOEMAKER. 15
